UNITED STATES PATENT OFFICE

2,635,767

COIL HANDLING APPARATUS

James S. Burge and Richard M. Goodwin, Anderson, and Hilton J. McKee, Middletown, Ind., assignors to General Motors Corporation, Detroit, Mich., a corporation of Delaware

Original application March 11, 1947, Serial No. 733,758. Divided and this application June 23, 1950, Serial No. 169,935

6 Claims. (Cl. 214—8)

1

This application is a division of application Ser. No. 733,758, filed March 11, 1947, which discloses a machine for winding a coil on one of a plurality of forms supported by a rotary conveyor or dial which is indexed to carry the coil to a taping station where tape is applied to the coil and to carry the taped coil to a station where it is ejected and is received by a stacking rack.

The object of the invention claimed in the present application is to provide for the stacking of a predetermined number of coils upon a stacking rack and for replacement automatically of a full rack by an empty one. To accomplish this, the machine provides a rotary conveyor or dial carrying a plurality of coil receiving racks, one of which is located in a position to receive coils as they are ejected from coil holders at the ejecting station and a mechanism for automatically indexing the stacking rack conveyor when the rack at the ejecting station has received a certain number of coils.

Further objects and advantages of the present invention will be apparent from the following description, reference being had to the accompanying drawings wherein a preferred embodiment of the present invention is clearly shown.

In the drawings:

Fig. 1 is a fragmentary front view of the machine showing the coil stacker, the point in section being taken on line 1—1 of Fig. 2.

Fig. 2 is a view in the direction of arrow 2 of Fig. 1.

Fig. 3 is a fragmentary plan view of the machine showing the coil form dial and a portion of the coil ejector.

Fig. 4 is a plan view of the stacker rack dial and supporting frame looking in the direction of arrow 4 of Fig. 1.

Fig. 5 is a section view on line 5—5 of Fig. 4.

Fig. 6 is a perspective view of a stacking rack.

Fig. 7, drawn to a larger scale than Fig. 5, is a sectional view on line 7—7 thereof.

Fig. 8 is a sectional view on line 8—8 of Fig. 7.

Fig. 9 is a front view of mechanism for operating the ejector and stacker.

Fig. 10 is a view on line 10—10 of Fig. 9.

Referring to Figs. 9 and 10, a power driven gear 130 is connectible by a clutch I with a shaft 134 which is connected with a sprocket 136 connected by a chain 140 with a sprocket 141 connected with a shaft 142 which drives a stacker operating mechanism to be described. A coupling 147 connects gear 130 with a shaft 148 which drives a cam 153 engaging a roller 180 carried by a lever

181 pivoted on a bracket 159a and urged down by a spring 181a and connected by an adjustable link 182 with a lever 183 fixed to a shaft 184 journaled in a bracket 185 attached to a bar 185a suspended from a table 101.

Following the indexing of a dial D (Fig. 3) which carries coil forms and holders 350 successively to a winding station W, a taping station T and an ejecting station E, clutch I is tripped automatically as disclosed in application Ser. No. 733,758 to effect operation of a coil ejector to remove the coil from the form 350 at station E. The coil ejector comprises fingers 900 (Fig. 9) operated by shaft 901 journaled in bearings supported by housing 902 carried by bracket 903. Shaft 901 is connected by arm 904 and link 187 with arm 186 operated by shaft 908. Shafts 184 and 908 are connected by a torque-limiting clutch comprising parts 905, 906 urged together by a spring 907. Clutch part 905 and bracket 185 support shaft 908 in alignment with shaft 184. If ejection of a coil at station E is abnormally resisted, the clutch part 906 will move right (Fig. 9) against the pressure of spring 907 to disconnect shaft 908 from shaft 184 and to cause flange 911 of clutch part 906 to operate a switch SW6 to cause the machine to stop as described in application Ser. No. 733,758.

The ejected coils fall around the detachable head 930 of a rack 931 (Fig. 6) having parallel rods 932 which support the head 930 and which are attached to plates 933, 934 and 935. A tube 936 is attached to plates 934 and 935 and plate 935 has a hole 937. There are eight of these racks or coil stackers 931 and they are supported by a dial 940 carrying pins 941 (Fig. 5) each of which is received by a tube 936, and studs 942 each of which is received by a hole 937 in the plate 935. In this way the racks 931 are located on the dial so that the noses 930a of the heads 930 face outwardly. Therefore, when a rack 931 arrives at the ejecting station its head 930 will be located so as to receive the coils as they are ejected.

Each rack 931 is intended to receive a predetermined number of coils. When the rack is full it is moved away from the ejecting station and an empty rack is brought to the ejecting station. The full rack is removed and replaced by an empty one. Therefore the dial 940 is caused to move intermittently after a predetermined number of operations of the machine. For this purpose the dial 940 is supported by a shaft 943 (Fig. 5) journaled in bearings 944 and 945 supported by the cover 946 of a box 947 enclosing the dial.

driving mechanism. Sprocket gear 136 operated by shaft 134 (Fig. 9) drives chain 140 which drives sprocket 141 connected with shaft 142 journaled in a bearing support 943 (Fig. 4). Through a speed reducer 949, shaft 142 drives a shaft 950 which operates a cam 951 (Fig. 7) rotating clockwise. As the cam 951 rotates, it picks up a roller 952 carried by a lever 953 pivoted on a screw 954 and causes the lever to move to position 953'. Lever 953 carries a pivot 955 for a pawl 956 engageable with a ratchet 957 attached to shaft 943. The pawl 956 carries plates 958 located above and below the ratchet 957 so that the ratchet may support the pawl vertically. A spring 959 connecting the pawl 956 and the lever 953 urges the pawl toward the ratchet. The function of cam 951 is to move the pawl so that it will pick up a tooth on the ratchet. The movement of the ratchet clockwise is effected by a spring 960 connecting the lever 953 with a screw 961 threaded through the box 947 and locked in adjusted position by a nut 962. The spring 960 effects one-eighth revolution of the dial, motion of lever 953 clockwise being limited by a screw 963 attached to a bracket 964 and locked in adjusted position by a nut 965. Overtravel of the dial 940 is prevented by a lever 967 pivoted at 968 on a block 939 and which is caused to move into the position shown in Fig. 8 in order to receive the lower end of a pin 941 on the dial. This position of lever 967 is effected by clockwise movement of lever 953 which picks up a washer 970 surrounding a rod 971 passing through a hole in the lever 953 and causes said washer to push against a spring 972 and the latter against a flange 973 of rod 971 and causes the rod to push against a pin 974 pivotally connecting the rod with lever 967. Thus the lever 967 is forced into blocking position by yielding pressure. Its blocking position is indicated diagrammatically in Fig. 4. The rebounding of the dial D and pin 941 counterclockwise from the lever 967 is prevented by the engagement of another pin 941 with a lever 975 pivotally supported at 976 by a bracket 977 and urged into rebound blocking position by a spring 978.

During counterclockwise movement of lever 953 by cam 951, lever 953 engages a nut 980 locked on shaft 971 by a nut 981. This is caused to move left (Figs. 7 and 8) to rotate lever 967 away from the pin 941 so that the dial can turn again. The indexing of dial 940 into a new position starts before lever 967 is moved again into position for blocking the next pin 941 which comes around. The timing between cam 951 and the main cam shaft 148 (Fig. 9) is such that the shaft 148 makes, for example, 60 revolutions for each revolution of cam shaft 950. Therefore the dial 940 indexes automatically whenever a rack at the ejecting station receives, for example, 60 coils. When the rack 931 is full and 60 is removed from the turntable 948, its head 930 is removed and stored at the machine. Removal of the head 930 exposes an eye 933a attached to plate 933. The full rack can be attached to a chain conveyor having a hook for engaging the eye 933a.

While the embodiment of the present invention as herein disclosed, constitutes a preferred form, it is to be understood that other forms might be adopted.

What is claimed is as follows:

1. Coil handling apparatus for use with a coil winding machine, said apparatus comprising a conveyor having holders for supporting coils, means for indexing the conveyor intermittently 75

to move coils successively to an ejecting station, means at the ejecting station for removing the coil from its holder while at the ejecting station and allowing the coil to gravitate from the holder, a stacker dial, a plurality of vertically disposed racks supported by the stacker dial and which are positioned by the indexing of the stacker dial successively in alignment with the coil ejector to receive the coil which gravitates from the coil-holder, a stacker dial indexer, a mechanism functioning in response to completion of indexing the conveyor to operate the coil ejector and means operated by said mechanism for causing operation of the stacker dial indexer after a certain number of operations of the coil ejector.

2. A machine according to claim 1 in which the stacker dial indexer is operated by a spring, and in which a rotary cam is driven by the ejector operating mechanism at reduced speed so that it rotates once during a certain number of ejector operations and in which the cam operates during one revolution to stress the spring and then release it.

3. A stacker comprising a conveyor for supporting racks which receive articles ejected from a machine which produces them, means for indexing the conveyor and comprising a rotatable ratchet, a pawl, spring means for causing the pawl to contact the ratchet, a cam follower connected with the pawl, an operating shaft, a cam driven thereby and engageable with the follower and contoured to move the pawl back along the ratchet to a ratchet-tooth engaging position and then to move away from the path of movement of the follower, and a spring connected with the follower, said spring being stressed during operation of the cam to back the pawl and being released when the cam leaves the follower to effect movement of the pawl to rotate the ratchet.

4. A stacker according to claim 3 in which the conveyor is provided with a series of equally spaced stop members projecting therefrom, a stop element supported for movement into and out of the path of movement of a conveyor stop member and means connected with the follower for causing the stop element to move into the path of movement of a conveyor stop member as the pawl closely approaches the end of its ratchet turning movement, said means providing a lost motion connection to allow the stop element to remain in said position until the pawl approaches closely to the end of its back-up movement.

5. A stacker according to claim 3 in which the conveyor is provided with a series of equally spaced stop members projecting therefrom, a stop element supported for movement into and out of the path of movement of a conveyor stop member and means connected with the follower for causing the stop element to move into the path of movement of a conveyor stop member as the pawl closely approaches the end of its ratchet turning movement, said means providing a lost motion connection to allow the stop element to remain in said position until the pawl approaches closely to the end of its back-up movement and means for preventing rebound of the conveyor stop member from the stop element.

6. A stacker comprising two parallel shafts, a conveyor dial driven by one of the shafts and adapted to support racks which receive articles ejected from a machine which produces them, means for driving the other shaft, a ratchet connected with the conveyor shaft, a lever, a pawl pivotally supported by the lever, spring means

urging the pawl into contact with the ratchet, a cam follower carried by the lever, a cam connected with the driving shaft and engageable with the follower and contoured to move the pawl back along the ratchet to a ratchet-tooth engaging position and then to move away from the path of movement of the follower, a spring connected with the lever, said spring being stressed during back-up movement of the pawl and being released when the cam leaves the follower to cause the pawl to rotate the ratchet, a series of 10 equally spaced stops projecting from the dial, a lever mounted for movement into and out of the path of movement of a stop, means for transmitting movement from the first lever to the second lever to cause the latter to move into the path of movement of a stop as the pawl closely approaches the end of its ratchet-turning movement and to cause the second lever to be retracted from the stop as the pawl closely approaches 15 the end of its back-up movement, a third lever mounted for movement into and out of the path of movement of a conveyor stop and a spring which urges the third lever into the path of

5

10

15

movement of the conveyor stop, said third lever presenting to the conveyor stop a surface which the conveyor stop engages to cam the third lever away from its path of movement, said surface having length such that the stop leaves the surface as the stop strikes the second lever whereupon the spring last mentioned returns the third lever to normal position, said third lever having a surface which, when said lever is in normal position, is presented to the conveyor stop on the side thereof opposite to the side of the conveyor stop which engages the second lever.
